DENTAL IMPRESSION TRAY

Van Cortlandt Eliot, Garden City, N. Y.

Application January 29, 1948, Serial No. 5,120

7 Claims. (Cl. 32—17)

1

This invention relates to dental impression trays, and more particularly to such a tray having means operable to compress a plastic molding compound against all the parts of the mouth to which it is to be applied.

In the manufacture of dentures it is customary to place a plastic molding compound in the recess of a relatively rigid tray, and to force the compound against the gums to obtain an impression of the contours of the mouth and gums, from which a dental plate may be manufactured. The force applied when using the conventional dental impression tray can, however, be applied in only one direction, upwards, when taking an impression of the upper gums, and downward when taking an impression of the lower gums. Naturally, as the force is applied, the plastic will slide over the various irregularities of the gums and the ridges of the hard palate. The scoring thus formed in the plastic material as it is inserted into place is never entirely eliminated when the material is forced into its final position, with the result that an accurate mold of the mouth is not obtained, and the dentures manufactured therefrom will present voids between the denture and the mouth surface tending to reduce the suction contact between the denture and the mouth surface. Such dentures will not adhere firmly to the mouth when in place, and require the use of an adhesive compound to anchor them firmly in place. Even with the use of such an adhesive compound, a bite pressure of more than fifteen or twenty pounds will cause the denture to become dislodged.

A further disadvantage of conventional dental impression trays is that no means is provided for securing an accurate impression of the rearmost portions of the mouth. As pressure is applied, the molding compound tends to flow rearward from the tray, and the pressure applied to the rearmost portion of the molding compound is insufficient to obtain any accurate impression of that portion of the mouth surface.

It is an object of this invention to provide a dental impression tray embodying means to apply a three-way pressure to the molding compound contained therein so that an accurate impression of the interior surface of the mouth may be obtained, which may be employed for the manufacture of a denture which will conform closely to the contours of the mouth so that a positive suction fit may be obtained.

It is a further object of this invention to provide a dental impression tray embodying means

to apply auxiliary pressure to the molding compound contained therein against the rearmost portions of the gums so as to obtain an accurate impression thereof.

5 Other and further objects and advantages of my new and improved dental impression tray will become apparent as the disclosure proceeds.

In general my invention comprises a dental impression tray having a base plate and an interior wall shaped to conform generally to the contours of the mouth. In the case of a tray adapted to make an impression of the upper gums, the interior wall will of course have the general contour of the hard palate, and will form a continuous surface between each leg of the base plate. In the case of a tray adapted to make an impression of the lower gum, the interior wall will be bent upwardly from the base plate at an angle approaching the perpendicular and will not form a continuous surface between the legs of the base plate, space being left to accommodate the tongue. A handle portion extends from the forward end of the base plate.

The exterior walls of the tray are formed by 25 two compressible wall sections which lie at right angles to the plane of the base plate and which are fixed to the base plate at the rear end thereof as by welding or riveting, or they may be formed integrally with the base plate. The wall sections are curved to conform to the exterior curvature of the base plate from the point of attachment thereto to the handle section thereof, at which point the wall sections are bent outwardly to form straight arms, by means of which the wall sections may be laterally compressed.

35 Dam-forming sections are hingedly attached to the rearward end of each leg of the base plate. These sections are conformed to the general shape of the rear end of the gums. In the case of the tray adapted to form an impression of the upper jaw the dam-forming sections are connected by a bar curved to the general outline of the hard palate. In the case of the tray adapted to form an impression of the lower jaw no connection is provided between the dam-forming sections. Each dam-forming section is defined by a base portion and interior and exterior wall portions, the wall portions lying roughly at right angles to the plane of the base portion. Means are provided at or near the upper edge of the exterior wall portion whereby a wire or other means to swing the dam-forming sections about their hinged axis may be attached.

40 A lever is swingably fixed to the handle section 50 of the base plate as by a lug and pin attachment.

The wire or other means of movement of the dam-forming section is led from the dam-forming section to a point approximately midway of the lever, whereby a manipulation of the lever will impart upward rotary motion to the dam-forming section.

As will be apparent to those skilled in the art, when the new and improved dental impression tray filled with plastic material has been forced into position over the gums, pressure exerted by forcing together the arms of the exterior wall sections will force the plastic material firmly against the outer surface of the gums, thereby forming an accurate impression thereof, and will at the same time pull the interior wall sections of the tray forward, thus pressing the plastic material contained within the tray firmly against the interior surfaces of the gums and against the palate, thereby forming an accurate impression thereof.

The lever controlling the movement of the dam-forming sections is then manipulated, the manipulations forcing the dam-forming sections and their contained plastic material firmly against the gums, thereby to obtain an accurate impression of the rearward portion of the gum surface.

In order to facilitate an understanding of my invention, reference is made to the accompanying drawing, in which:

Fig. 1 is a top plan view of the new and improved dental tray of the type adapted for use in taking an impression of the upper jaw, the solid lines indicating the position of the exterior walls as they would appear in normal position, the dotted lines indicating the position of the exterior walls as they would appear when compressed.

Fig. 2 is a cross-sectional view of the new and improved dental tray as it would appear when viewed along line 2-2 of Fig. 1, showing the dam-forming section as it would appear when in lowered position.

Fig. 3 is a side elevational view of the new and improved dental tray showing the dam-forming section as it would appear when in raised position.

Fig. 4 is a top plan view of the new and improved dental tray of a design adapted for use in taking an impression of the lower jaw, and

Fig. 5 is a cross-sectional view of the new and improved dental tray as it would appear when viewed along line 5-5 of Fig. 4, the solid lines showing a dam-forming section as it would appear in lowered position, the dotted lines showing a dam-forming section as it would appear when in raised position.

Similar reference characters refer to similar parts throughout the several views of the drawing and the specification.

My dental impression tray is preferably fabricated from light-gauge soft sheet metal, or a resilient plastic material.

As illustrated in Figs. 1 through 3, the tray comprises a flat base plate 1 of generally arcuate Y-shaped contour presenting leg sections 2 and 3 and a handle section 4. An interior wall 5 connects the leg sections 2 and 3, the wall 5 rising smoothly from the inner surfaces of the leg sections 2 and 3 to form a convex retaining wall generally shaped to conform to the contours of the hard palate.

Resilient exterior wall sections 6 and 6' are fixed to the base plate 1 at or near the outer portion of the ends of its leg sections 2 and 3. The exterior wall sections 6 and 6' may be riveted

or welded to the base plate 1, but are preferably formed from the same piece of material by stamping out a blank in the proper design, and by bending up the exterior wall-forming material at right angles to the base plate 1, so that the plane of the exterior wall sections 6 and 6' will lie in a plane roughly perpendicular to the plane of the base plate 1. Exterior wall sections 6 and 6' present arm portions 7 and 7' which are curved to follow the outer outline of the leg sections 2 and 3, and manipulating handle portions 8 and 8' which are flared outwardly at hip portions 9 and 9', whereby the exterior wall sections 6 and 6' may be compressed to the position indicated by the dotted lines shown in Fig. 1.

A dam-forming plate 10 is swingably mounted on the ends of the leg portions 2 and 3 as by hinges 11 and 11'. The dam-forming plate 10 comprises outer walls 12 and 12', base walls 13 and 13', and a bar portion 14, which rises arcuately from and connects with the interior edges of the bottom wall portions 13 and 13'. The bar portion 14 overlies in part the interior wall 5, and conforms generally to the contour of the hard palate.

A lever 15 is mounted on the lower side of the handle section 4 as by a lug 16 and pin 17, in a position convenient for manipulation. The lever lever 15 is connected with the outer walls 12 and 12' of the dam-forming plate 10 as by a wire 18 secured through holes 19 and 19' located near the upper edges of the outer walls 12 and 12', and passing through a hole 20 near the center of the lever 15, whereby the dam-forming plate 10 may be caused to rotate about its hinged axis by manipulation of the lever 15.

As illustrated in Figs. 4 and 5 the dental impression tray presents a base plate 1, exterior walls 6 and 6', and a lever 15 of the same type as illustrated in Figs. 1 through 3. An interior wall portion 21 arises from the inner edges of the leg sections 2 and 3 to a height slightly less than that of the exterior wall sections 6 and 6'.

Dam-forming sections 22 and 22' are hingedly connected to the ends of legs 2 and 3 as by hinges 23 and 23'. Dam-forming sections 22 and 22' present outer walls 24 and 24', base walls 25 and 25', and inner walls 26 and 26', the outer and inner walls being bent upward at an angle of about 90° to the base walls 25 and 25', which are of sufficient width to permit the outer walls 24 and 24' to clear the exterior walls 6 and 6', and to permit the inner walls 26 and 26' to clear the interior wall portion 21 when the dam-forming sections 22 and 22' are rotated about their hinged axes.

A wire 18 leads from holes 27 and 27' located near the upper edges of outer walls 24 and 24' through the hole 20 in the lever 15, whereby the dam-forming sections 22 and 22' may be rotated upwardly by a forward motion of the lever 15 to the position indicated by the dotted lines in Fig. 5.

When using my new and improved dental impression tray to secure an impression for a full denture, plastic material of any type useful in taking dental impressions is inserted in the trough defined by base plate 1, exterior wall sections 6 and 6', and interior walls 5 or 21, and the tray with its plastic content is forced against the gums. The force exerted will tend to extrude plastic from the ends of the leg portions 2 and 3 onto the dam-forming plate 10 or dam-forming sections 22 and 22'. When the tray has been forced to its ultimate position on the gums, the

operator will squeeze together the manipulating handle portions 8 and 8' of the exterior wall sections 6 and 6' so as to compress them into the position shown by the dotted lines in Fig. 1. The force thus exerted against the plastic material contained in the tray will tend to press it firmly against the outer surface of the gums so as to register an accurate impression thereof on the plastic material. At the same time a forward pull will be exerted on the base plate 1 at the point of connection between the base plate 1 and the exterior wall sections 6 and 6', thus forcing the interior walls 5 or 21 forward against the plastic material in the trough whereby to register an accurate impression of the contours of the inner portion of the gums and of the palate upon the plastic material.

The lever 15 is then manipulated to rotate the dam-forming plate 10 or the dam-forming sections 22 and 22' against the gums, forcing the plastic material firmly against the rearmost portion of the gums whereby to register an accurate impression thereof. The rearmost edge of the bar portion 14 and of the base walls 13 and 13' or 25 and 25' will press firmly against the upper palate and gums to form a post dam, insuring an accurate fit and excellent suction qualities in any denture manufactured from the impression taken by the use of this new and improved dental impression tray.

The tray may also be used to secure impressions for partial dentures. When so using the tray the dentist will place the empty tray in the patient's mouth and mark thereon the position of the remaining teeth. With a dental drill or burr he may then cut away sufficient of the tray material to allow the patient's remaining teeth to pass through the openings thereby provided. He will then fill the tray with plastic material and proceed to take an impression as described above.

It is to be noted that the tray as designed will not cause discomfort to the patient and will not press against the lip cords found in the forward part of the mouth since when the exterior wall sections 6 and 6' are fully compressed, there will remain a space between the hip portions 9 and 9' thereof, so that no part of the tray will press against the cords or interfere therewith.

By the use of my new and improved dental impression tray I have been able to manufacture dentures which will take a 60-pound bite pressure without loosening in the mouth, and which enable the user to chew with a lateral motion without loosening. The tray is sturdy and may be easily fabricated by stamping from a sheet of material. Dentures manufactured from impressions taken by the use of this tray will fit the mouth accurately and will firmly adhere to the mouth by means of suction alone, no adhesive being required.

Having now described my invention, what I claim as new is:

1. In a dental impression tray, the combination of a Y-shaped base plate having leg sections and a handle section, an interior wall arising from the inner edges of the said leg sections, a dam-forming section hingedly attached to the ends of the said leg sections, the said dam-forming section presenting outer wall portions, base wall portions, and a dam-forming plate portion connecting the inner edges of the base wall portion, the said plate portion being curved to generally conform to the outline of the hard palate, a lever hingedly attached to the handle section of the

base plate, and means to connect the said lever to the upper part of each outer wall portion of the dam-forming section whereby the said dam-forming section may be rotated about its hinged axis.

2. In a dental impression tray, the combination of a Y-shaped base plate having leg sections and a handle section, an interior wall arising from the inner edges of the said leg sections, a dam-forming section hingedly attached to the end of each of the said leg sections of the base plate, each of said dam-forming sections presenting an outer wall portion, a base wall portion, and an inner wall portion, a lever hingedly attached to the handle section of the base plate, and means to connect the said lever to the upper part of the outer wall portion of each dam-forming section whereby the said dam-forming section may be rotated about its axis.

3. In a dental impression tray, the combination of a Y-shaped base plate having leg sections and a handle section, an interior wall arising from the inner edges of the said leg sections, resilient exterior wall sections affixed to the outer edge of the said leg sections near the ends thereof, the said exterior wall sections presenting arm portions curved to generally follow the outer edges of the said leg sections of the base plate, and manipulating handle portions whereby the said arm portions may be laterally compressed, a dam-forming section hingedly attached to the ends of the said leg sections, the said dam-forming section presenting outer wall portions, base wall portions, and a dam-forming plate connecting the inner edges of the base wall sections, the said plate portion being curved to generally conform to the outline of the hard palate, a lever hingedly attached to the handle section of the base plate, and means to connect the said lever to the upper part of each outer wall portion of the dam-forming section, whereby the dam-forming section may be rotated about its axis.

4. In a dental impression tray the combination of a Y-shaped base plate having leg sections and a handle section, an interior wall arising from the inner edges of the said leg sections, resilient exterior wall sections affixed to the outer edges of the said leg sections near the ends thereof, the said exterior wall sections presenting arm portions curved to generally follow the outer edges of the said leg sections of the base plate, and manipulating handle portions whereby the said arm portions may be laterally compressed, a dam-forming section hingedly attached to the end of each of the said leg sections of the base plate, each of said dam-forming sections presenting an outer wall portion, a base wall portion, and an inner wall portion, a lever hingedly attached to the handle section of the base plate, and means to connect the said lever to the upper part of each outer wall portion of the dam-forming section, whereby the said dam-forming section may be rotated about its axis.

5. In a dental impression tray the combination of a Y-shaped base plate having leg sections and a handle section, an interior wall rising from the inner edges of the said leg sections, resilient exterior wall sections affixed to the outer edges of the said leg sections near the ends thereof, the said exterior wall sections presenting arm portions curved to generally follow the outer edges of the said leg sections of the base plate and manipulating handle portions whereby the said arm portions may be laterally compressed,

a dam-forming means hingedly attached to the ends of the said leg sections, the said dam-forming means presenting outer, base, and inner wall portions; a lever hingedly attached to the handle section of the base plate, and means to connect the said lever to the upper part of the outer wall portions of the dam-forming means, whereby the said dam-forming means may be rotated about its axis.

6. In a dental impression tray, the combination of a Y-shaped base plate having leg sections and a handle section, an interior wall arising from the inner edges of the said leg sections, the said interior wall connecting the leg sections of the base plate and being rounded to conform generally to the shape of the hard palate, a dam-forming section hingedly attached to the ends of the said leg sections, the said dam-forming section presenting outer wall portions, base wall portions, and a dam-forming plate portion connecting the inner edges of the base wall portion, the said plate portion being curved to generally conform to the outline of the hard palate, a lever hingedly attached to the handle section of the base plate, and means to connect the said lever to the upper part of each outer wall portion of the dam-forming section whereby the said dam-forming section may be rotated about its hinged axis.

7. In a dental impression tray, the combination of a Y-shaped base plate having leg sections and a handle section, an interior wall arising from the inner edges of the said leg sections, the said interior wall connecting the leg sections of the

base plate and being rounded to conform generally to the shape of the hard palate, resilient exterior wall sections affixed to the outer edges of the said leg sections near the ends thereof, the said exterior wall sections presenting arm portions curved to generally follow the outer edges of the said leg sections of the base plate, and manipulating handle portions whereby the said arm portions may be laterally compressed, a dam-forming section hingedly attached to the ends of the said leg sections, the said dam-forming section presenting outer wall portions, base wall portions, and a dam-forming plate connecting the inner edges of the base wall sections, the said plate portion being curved to generally conform to the outline of the hard palate, a lever hingedly attached to the handle section of the base plate, and means to connect the said lever to the upper part of each outer wall portion of the dam-forming section, whereby the said dam-forming section may be rotated about its hinged axis.
